UNITED STATES PATENT OFFICE.

THOMAS CONNOR, OF SAN FRANCISCO, CALIFORNIA, ASSIGNOR OF FORTY-FIVE ONE-HUNDREDTHS TO G. L. CONENS, OF SAN MATEO, CALIFORNIA, AND TEN ONE-HUNDREDTHS TO E. J. HALL, OF SAN FRANCISCO, CALIFORNIA.

SHOCK-ABSORBING DOOR AND GATE LATCH.

1,055,613.

Specification of Letters Patent. Patented Mar. 11, 1913.

Application filed September 18, 1911. Serial No. 649,894.

To all whom it may concern:

Be it known that I, THOMAS CONNOR, citizen of the United States, residing in the city and county of San Francisco and State of California, have invented new and useful Improvements in Shock-Absorbing Door and Gate Latches, of which the following is a specification.

My invention relates to door and gate latches of that class in which twin catches are so disposed as to engage a latching bolt when the door swings into a closed position; one of the catches being retracted by the passing bolt, and returning immediately afterward, and the other one remaining in its normal position to prevent a further swinging of the door. The latching devices are retracted, depressed, or moved in various ways to allow the door to be again opened.

It is a particular object of my invention to provide a device which operates to prevent undue shock or noise when the door swings into position and is suddenly checked.

My invention also comprises details of construction which will be more fully explained by reference to the accompanying drawings, in which—

Figure 1 is a broken perspective view of a catch. Fig. 2 is an end view. Fig. 3 is a top view showing the latch and catch. Figs. 4 and 5 show the catch in its engaged and disengaged position. Fig. 6 is a perspective view with the case broken away showing the operating means. Fig. 7 is an edge view of the door partly broken to show the operating device. Fig. 8 shows the divergent latches and shock absorbers. Fig. 9 is a perspective of one of the latches in Fig. 8.

As shown in the drawings, A represents a casing in which the latches 2 are fitted. These latches, to resist the shock of the swinging door, may be diverged from each other, and the channels in which they are fitted are sufficiently deeper than the length of the catches to allow them to be retracted whenever the catch upon the door passes them.

Spring 3 are fitted in chambers at the rear ends of the catches and tend to normally hold the catches projected into position to engage with the latches, as will be hereinafter described. The catches 4 nor-

mally project from casings 5 which are mortised into the door, and they are so disposed that they may be retracted, depressed or raised out of the line of travel with the latches for the purpose of releasing them to allow the door to be opened.

It will be understood that when a door, and especially a heavy door is swung so as to latch by the engagement of the catch with the latch, there will be an abrupt stoppage, and when the door is a heavy one the shock and noise will be very considerable. In order to overcome this noise and shock, I have shown elastic shock absorbers 6 which may be made of rubber or springs, and these are placed behind the latches in the direction from which the shock will be given, thus yielding sufficiently for the purpose desired.

It will be seen that when the catches have passed into the space between the latches the door will be prevented from opening until the catches are in some way released from the engagement.

I have designed these devices particularly for gates in office rails and for like purposes. Therefore, as shown in Figs. 1, 2 and 6, the catch is pivoted in the rear end of its casing and may be depressed so as to allow the gate to be opened.

Figs. 4 and 5 show a stem 7 having a suitable knob upon the upper end, and the catch is normally held in place by a spring 8. When the knob is pressed the catch will be depressed below the level of the latches which will thus be free to move. In some cases, such as where swinging doors are employed in pantries or restaurants, it is desirable to have the latch operated by the foot. In such a case the latch may have a threaded stem 9 with an eye 10 at the end and this may be conveniently connected by a hook bolt 11 with cross bars 12 projecting upon each side near the bottom of the door. Thus when a waiter is passing through the door with an armful of dishes he can readily place his foot upon the bar 12 and disengage the catch from the latch so that the door may swing open. As soon as he has passed, the door will swing into closed position and be locked.

The above arrangement of the latches and catches allows a very soft yielding spring to be used behind the latches, which spring

will be easily compressed whenever the latch passes, and thus the door will close even when opened to a very small extent. The cushions against which the latches are 5 pressed when the door closes will yield so that the shock will be almost entirely absorbed.

To prevent the latches from being forced out of their pockets by the springs which 10 operate in the direction of their length, the latches are formed with shoulders 13, and a pin 14 fixed to and projecting from a central dart-shaped section of the casing between the latches 2 and extending within 15 the line of these shoulders act as stops to limit the movements of the latch in the direction of its length, while allowing it to move freely in a transverse direction.

Having thus described my invention what 20 I claim and desire to secure by Letters Patent is—

1. A door and gate latch, including a pair of spring pressed repressible latches, upon one member, a catch pivoted at the inner 25 end in the other member, and having a spring by which it is normally held up in horizontal line with the latches, a door having a vertical chamber and a pocket to receive the catch, and a rod connected with

the catch extending downward through the 30 door chamber, and having foot pieces, extending through the door to either side.

2. A door and gate latch, including a pair of spring pressed repressible latches, shoulders formed in the latches, and a central 35 dart-shaped section lying between the latches and having oppositely extending stop pins lying in the space formed by the shoulders to limit the longitudinal movement of the latches.

3. A door and gate latching device, including a casing having channels divergent outwardly, latches slidable in the channels, springs by which the latches are normally projected, and against which they are repressible, said latches having transverse channels, a pin fixed transversely in the casing to limit the movement of the latches, 45 chambers in the walls of the casing, and elastic cushions therein projecting to receive the lateral impact of the latches.

In testimony whereof I have hereunto set my hand in the presence of two subscribing witnesses.

THOMAS CONNOR.
